[57] CLAIM

The ornamental design for a data processing system console, as shown.

DESCRIPTION

FIG. 1 is a top, right and front perspective view of a first embodiment of a data processing console showing our new design.

FIG. 2 is a top, left and rear perspective view thereof.

FIG. 3 is an enlarged top, front view of the operator's full panel of FIG. 1 shown separately for clarity of illustration only.

FIG. 4 is a top, right and front perspective view of a second embodiment thereof as shown in FIG. 1.

FIG. 5 is a top, left and rear perspective view of the console of FIG. 4.

FIG. 6 is an enlarged top, front view of the operator's control panel of FIG. 4, shown separately for clarity of illustration only.
